UNITED STATES PATENT OFFICE.

JOHN MORTON, OF THORNVILLE, MICHIGAN.

FENCE.

SPECIFICATION forming part of Letters Patent No. 230,645, dated August 3, 1880.

Application filed December 4, 1879.

To all whom it may concern:

Be it known that I, JOHN MORTON, of Thornville, in the county of Lapeer and State of Michigan, have invented certain new and 5 useful Improvements in Fences, of which the following is a specification.

My invention relates to that class of fences known as "portable fences," constructed in sections, and having posts to which said sections are secured.

My invention principally consists in a portable fence-post composed of a horizontally-extending base, two uprights extending therefrom, one of which is fixed and the other of which is movable relatively to the fixed upright, a brace extending from the fixed upright to the base, and means, preferably consisting of a wedge, acting upon the movable upright to cause it to clamp between it and the fixed upright the longitudinally-extending sections or portions of the fence. Such post is preferably also provided with a diagonal brace, to which the fixed upright is secured, and which is provided at one end with a loop or hook for the reception of the clamping-wedge.

The invention also consists in details of construction hereinafter to be explained.

In the accompanying drawings, Figure 1 represents a side view of a portion of a portable fence embodying my invention. Fig. 2 represents a transverse section of the fence on the line *x* *x*, Fig. 1; and Fig. 3 represents a plan of one of the posts and a portion of two fence-sections.

Similar letters of reference designate corresponding parts in all the figures.

The fence-sections which are to be united together to form the fence may be variously constructed. They may be composed, like the sections A in Fig. 1, of upright boards or cleats, *a*, to which are secured longitudinally-extending boards or strips, *b*; or, if desirable, in order to make them lighter, or for other reasons, they may be made like the section B, in which longitudinal boards or strips *b* are used only at each side, and the central part is filled up by wires *c*, which are run back and forth and secured by staples.

C designates posts which are employed to secure the sections of fence together, so as to form a continuous line. These posts are each composed of a horizontally-extending base-piece, *d*, which rests upon the ground, and is sufficiently long to afford a stable bearing.

From the base-piece *d* there extends upward a fixed upright, *e*, secured, at or near the top, to an iron brace, *f*, and a movable upright, *g*, which, as here represented, is pivoted to the base-piece *d*, and movable relatively to the fixed upright.

As here represented, the brace *f* is secured at its lower end to the base-piece *d*, and is provided at the top with a laterally-extending portion, *f'*, which serves as a guide for the movable upright as it is moved forward or back.

The boards *b* of two adjacent sections are inserted between the two uprights, so as to overlap each other, as represented in Fig. 3, 70 and means employed for securing the movable upright *g* to the fixed upright *e*, so as to clamp the fence-sections securely between them.

As here represented, the brace *f* terminates at the upper end in a hook or bend, *f'*, in 75 which a wedge, *h*, may be inserted for forcing the movable upright *g* toward the fixed upright *e*; but in lieu of such wedge a screw or other means might be employed.

If desired, the longitudinally-extending 80 portions of the fence might consist simply of wires, and the uprights of the post be notched to receive them.

By my invention I provide a portable fence which may be very readily erected or taken 85 down for removal, and hence one which can be moved from place to place at a small expense.

What I claim as my invention, and desire to secure by Letters Patent, is— 90

1. A portable fence-post composed of a horizontally-extending base-piece, *d*, a fixed upright, *e*, an iron brace, *f*, extending from said base-piece to said upright, a movable upright, *g*, and means acting on said movable upright to cause it to securely hold and clamp between it and the fixed upright the longitudinally-extending portions of the fence, substantially as specified.

2. The portable fence-post composed of the base *d*, the fixed upright *e*, the pivoted movable upright *g*, and the brace *f*, to which the fixed upright is secured, and which is provided at the end with a loop or hook, *f'*, and the wedge *h*, adapted to be inserted in the 105 said loop or hook, substantially as specified.

JOHN MORTON.
